CLAIM

The ornamental design for a print tower device, as shown and described herein.

DESCRIPTION

FIG. 1 illustrates a front, right, perspective view of a print tower device according to the invention.

FIG. 2 illustrates a front view of the print tower device shown in FIG. 1.

FIG. 3 illustrates a rear view of the print tower device shown in FIG. 1.

FIG. 4 illustrates a left side view of the print tower device shown in FIG. 1.

FIG. 5 illustrates a right side view of the print tower device shown in FIG. 1.

FIG. 6 illustrates a top view of the print tower device shown in FIG. 1; and,

FIG. 7 illustrates a bottom view of the print tower device shown in FIG. 1.

The ornamental design that is claimed is shown in solid lines in the drawings. The broken lines shown in the drawings represent portions of the print tower device and environment that form no part of the claimed design.

1 Claim, 7 Drawing Sheets
